UNITED STATES PATENT OFFICE.

RALPH B. WARNER AND MELVILLE L. SHROAT, OF MARION, INDIANA.

OIL-BURNER.

1,077,178.

Specification of Letters Patent.

Patented Oct. 28, 1913.

Application filed May 5, 1913. Serial No. 765,609.

To all whom it may concern:

Be it known that we, RALPH B. WARNER and MELVILLE L. SHROAT, citizens of the United States, residing at Marion, in the 5 county of Grant, State of Indiana, have invented a new and useful Oil-Burner, of which the following is a specification.

This invention relates to improvements in oil burners.

10 An object of the present invention is to provide an oil burner which may be readily positioned within a stove and will effectually heat the same.

15 A further object is to provide improved means whereby the air will be heated prior to its mixing with the gaseous fuel to thereby increase the efficiency of the burner.

20 A further object is to provide improved means whereby the liquid fuel will be effectually vaporized prior to its issuing from the delivery nozzle.

25 With the foregoing and other objects in view which will appear as the description proceeds, the invention resides in the combination and arrangement of parts and in the details of construction hereinafter described and claimed, it being understood that changes in the precise embodiment of the invention herein disclosed, can be made 30 within the scope of what is claimed, without departing from the spirit of the invention.

35 In the drawings accompanying this specification and forming a part thereof, the preferable form of our invention is illustrated, in which:—

40 Figure 1 is a view in perspective of our improved liquid burner. Fig. 2 is a vertical cross sectional view taken through the longitudinal axis of the burner.

45 Referring to the drawings in which similar reference numerals designate corresponding parts throughout the several views, 1 is a base with a cover or lid 2 fitting thereover, the said base and lid forming an air chamber 3 through which the air passes prior to its mixing with the fuel to form a combustible mixture. The base 1 and cover 2 are provided with the outstanding lugs 4 through which extend the bolts 5 to thereby provide means whereby the cover may be rigidly and at the same time detachably secured to the base. The rear end wall 6 of the air chamber extends a slight distance 50 above the side walls and rigidly secured thereto is the outstanding plate 7 upon

which rests the U-shaped box member 8, the same comprising a top and two side walls which taken in conjunction with the upstanding portion 9 of the cover 2 forms a 60 continuation of the air chamber or passage 3 and is offset a distance thereabove.

The cover or lid 2 is provided with two complete inclosing upstanding flanges 10 which thereby define two open pans or receptacles 11 and 12. The pans in question are used during the initial starting of the burner and serve as means for containing a limited amount of liquid fuel which is burned to thereby generate sufficient heat to 70 vaporize the liquid fuel which after having been once lighted, generates sufficient heat to maintain the fuel in a vaporized condition. The upstanding plate 9 disposed at and defining the rear end of the cover or lid 2 is 75 spaced a distance away from the end wall 6 of the base 1 so as to allow sufficient space for the passing of the air through the box-like member 8 down into the air chamber 3.

Arranged approximately longitudinally 80 central of the pans 11 and 12 and adjacent the front ends thereof are the upstanding mixer tubes 13—13, the same being formed integral with the cover 2 or may be rigidly secured thereto and the central opening 14 85 which extends therethrough communicating with the air chamber 3 as more clearly illustrated in Fig. 2 of the drawings.

From the foregoing it will be apparent that the air after it enters through the open 90 end of the box-like structure 8 which is adapted to extend through the outer wall of the stove to which our improved burner is to be attached, passes downward through the opening between the lid 2 and end wall 95 6 of the base 1 and into the air chamber 3 and becomes heated during the said passage and passes upward through the mixer tubes 13 in a highly heated condition, it being noted that the entire burner is formed of 100 metal and therefore readily conducts the heat from points adjacent the flame, throughout the entire structure.

A liquid fuel supply pipe 15 is provided with the coupling 16 from which the two 105 fuel supply pipes 17 lead, the same communicating with the control valves 18 which are preferably of the needle type. Leading from the two valves 18—18 are what are termed the feed pipes 19—19, the same extending through the open end of the box-like structure 8, extending downward into

the air chamber or passage 3, and extending along the under surface of the cover thereof. The pipes 19-19 pass upward through the cover 2 at points adjacent the rear ends of the pans 11 and 12 communicating with the upstanding pipes 20-20 to a height above the top of the mixer tubes 13 across which the pipes 20-20 then pass as at 21-21. The feed pipes then dip downward as at 22-22 and communicate with what are termed the fuel delivery nozzles 23-23, the same extending horizontal and passing through suitable apertures in the side walls of the mixer tubes 13-13 as illustrated. The delivery nozzles 23 are provided with the upwardly directed openings 24 through which the fuel, which at this point will be in a gaseous state, issues. In order to provide means whereby the delivery nozzles 23 may be cleaned at various times, the plugs 25 are threadedly secured to the ends thereof. The liquid fuel entering through the fuel supply pipes 17 passes through the regulating valves 18 and down through the air chamber 3 along the under surface of the cover, whereby the fuel will be heated. The fuel then passes upward through what are termed the fuel feed pipes which lead directly above and across the mixer tubes 13. A suitable deflector is mounted upon the said feed pipes 21 and comprises a broad flat plate adapted to deflect the flames in the usual manner and also to absorb a certain quantity of the heat therefrom and conduct the same to the feed pipes 21 to thereby successfully vaporize the fuel prior to its emission or exit from the supply nozzles 23. By providing the metallic base and cover which defines a suitable air chamber therein, the air will be heated prior to its mixture with the gaseous fuel, with the result that a high degree of efficiency will be obtained and that a highly combustible mixture of air and gaseous fuel will be obtained. Packed joints such as unions, etc., are disposed out of and at considerable distance from the burner with the result that little or no trouble will be experienced by a burning out of the packing disposed within the same. The pans 11 and 12 provide means for the burning of an initial charge of liquid fuel to thereby heat up the various parts of the burner for the vaporization of the liquid fuel which may be any suitable liquid such as gasoline, kerosene, or other suitable hydro-carbon.

Having thus fully described the invention, what we claim to be new and original with us is:—

1. An oil burner including a trough-like base, a cover therefor, mixer tubes extending through said cover and communicating with the air chamber defined by said base and cover, said cover stopping short of one end of said base allowing the ingress of air, delivery nozzles extending through the

side walls of said mixer tubes and adapted to deliver gaseous fuel therein, and fuel feed pipes extending above said mixer tubes communicating with said delivery nozzles and extending through said trough-like base. 70

2. An oil burner including a base, a cover therefor and stopping short of the end thereof, a box-like structure communicating with the open end of said base and adapted to supply air therein, mixer tubes positioned upon said cover and communicating with the air chamber defined by said base and cover, delivery nozzles extending through the side walls of said mixer tubes and adapted to deliver gaseous fuel therein, fuel feed pipes extending above said mixer tubes communicating with said delivery nozzles and extending through the said base, said pipes communicating with a liquid supply, and regulating valves disposed within said pipes. 80

3. An oil burner comprising a base, a cover therefor stopping short of one end thereof, said cover and base defining an air chamber, an open-ended box-like structure 90 communicating with the open top portion of said base and adapted to supply air therein, upstanding flanges upon the top of said cover and defining a fuel receiving pan for the initial starting of said burner, a mixer tube extending through said cover and communicating with said chamber, said mixer tube provided with an aperture extending through the side wall thereof, a delivery nozzle extending through said aperture and adapted to deliver gaseous fuel within said mixer tube, means for vaporizing liquid fuel and the supplying of the same to said delivery nozzle, and means controlling the supply of said liquid fuel. 100

4. In a device of the class described, a trough-like base, a cover therefor and stopping short of one end thereof, said base and cover defining an air heating chamber, a mixer tube positioned upon said cover communicating with said air chamber and provided with an aperture extending through the side wall thereof, a delivery nozzle extending through said aperture and adapted to supply gaseous fuel to the mixer tube, 110 a fuel feed pipe passing through said cover, upward and across the upper extremity of said mixer tube and communicating with said delivery nozzle, and a deflector disposed upon said feed pipe positioned above said mixer tube, said feed pipe extending through said air chamber and provided with a liquid fuel controlling valve. 120

5. In a device of the class described, a trough-like base, a cover therefor and stopping short of one end thereof, said cover provided with an upstanding plate at the open portion of said base, a box-like member disposed at the open portion of said base, abutting said cover upstanding plate 130

and adapted to supply air to the air chamber defined by said trough-like base and cover, upstanding flanges formed integral with the said cover and defining a liquid fuel receiving pan for the initial vaporizing of the fuel, a mixer tube upon said cover adjacent the one end of said pan and communicating with said air chamber, a fuel delivery nozzle extending through the side wall of said mixer tube and adapted to supply gaseous fuel therein, a vaporizing tube extending across and above the said mixer tube and adapted to vaporize the fuel passing therethrough, said vaporizing tube com-

municating with said delivery nozzle, and 15 a pipe extending through said air chamber communicating with said vaporizing tube and also communicating with a suitable liquid supply.

In testimony that we claim the foregoing 20 as our own, we have hereto affixed our signatures in the presence of two witnesses.
